(57) **CLAIM**

The ornamental design for a physical therapy device, as shown and described.

DESCRIPTION

FIG. 1 is a front/right/top perspective view of a physical therapy device showing our new design (a front/left/top would be a mirror image thereof);

FIG. 2 is a front elevational view thereof (a rear elevational view would be a mirror image thereof);

FIG. 3 is a left side elevational view thereof (a right side elevational view would be a mirror image thereof);

FIG. 4 is a top plan view thereof; and,

FIG. 5 is a bottom plan view thereof.

The uniformly broken lines in the drawings are for the purposes of illustrating portions of the physical therapy device, which form no part of the claimed design.

The physical therapy device is shown with a symbolic break in its length. The appearance of any portion of the article between the break lines forms no part of the claimed design.

1 Claim, 5 Drawing Sheets
